(57) **CLAIM**

The ornamental design for a golf divot tool as shown and described.

DESCRIPTION

FIG. 1 is an exploded front, right and top perspective view of a golf divot tool, showing my design;
FIG. 2 is a front elevation view thereof.
FIG. 3 is a rear elevation view thereof.
FIG. 4 is a left side elevation view thereof.
FIG. 5 is a right side elevation view thereof.
FIG. 6 is a top plan view thereof.
FIG. 7 is a bottom plan view thereof, and,
FIG. 8 is a front, right and top perspective view with the top element in a closed position.
The broken lines depict portions of the golf divot tool that form no part of the claimed design.
